UNITED STATES PATENT OFFICE

165,807

JEWELRY BOX

Milton Weill, New York, N. Y., assignor to Arrow
Manufacturing Company, Incorporated, West
New York, N. J., a corporation of New Jersey

Application May 17, 1951, Serial No. 15,224

Term of patent 3½ years

(Cl. D80—5)

To all whom it may concern:

Be it known that I, Milton Weill, a citizen of the United States, residing at New York, in the county of New York and State of New York, have invented a new, original, and ornamental Design for a Jewelry Box, of which the following is a specification, reference being had to the accompanying drawings, forming part thereof.

I claim:

The ornamental design for a jewelry box, as shown.

MILTON WEILL.
